UNITED STATES PATENT OFFICE.

TOKUTARO NISHIDA, OF SEATTLE, WASHINGTON.

NON-REFILLABLE BOTTLE.

1,064,851.

Specification of Letters Patent. Patented June 17, 1913.

Application filed March 25, 1912. Serial No. 685,994.

To all whom it may concern:

Be it known that I, TOKUTARO NISHIDA, a subject of the Emperor of Japan, and a resident of the city of Seattle, in the county of King and State of Washington, have invented certain new and useful Improvements in Non-Refillable Bottles, of which the following is a specification.

My invention has for one of its objects to 10 provide a simplified and improved construction of the above type, which, while being capable of ready removal by authorized parties, will safe-guard the latter as well as the trade against adulteration or 15 substitution with respect to the contents of the bottle.

A further object resides in the provision of novel valve securing mechanism.

Other objects will be set forth as my description progresses and those features of construction, arrangements and combinations of parts on which I desire protection, succinctly defined in my annexed claim.

Referring to the accompanying drawing 25 wherein like numerals of reference indicate like parts throughout: Figure 1 is a vertical section of my attachment applied as in use, the valve controlling device being adjusted to secure the valve closed. Fig. 2 30 is an elevation of the attachment and the upper end portion or neck of the bottle, the casing of said attachment being broken away and illustrating the valve controlling device in its releasing position, and Fig. 3 35 is a cross sectional view taken on line 3—3 of Fig. 1.

My invention comprises a casing 1 having its upper end portion externally screw threaded and provided with spaced apertures 2 which are normally closed by an annular flange 3' having threaded engagement with the said threaded portion of the casing. Flange 3' depends from a rotatable casing-closure 3, constituting a member 40 for advancing and retracting a valve controlling device 4, which latter is conveniently in the form of a stem fixed to said closure 3 and projecting through a perforated guard 5, fixed to said casing above 45 valve 6 and limiting upward movement of

the latter (see Fig. 2), as in my Patent 1,012,095. The lower end portion of stem 4 is provided with a shoulder 7 which during movement of said stem to its releasing position engages guard 5 to limit upward 55 movement of closure 3 immediately after flange 3' of the latter has uncovered apertures 2, and thereby prevent removal of the closure from casing 1, as shown in Fig. 2. Valve 6 which is adapted to seat flatly upon 60 the upper end of the bottle neck, is provided with a facing 6' of suitable yielding material, as for example, rubber or cork, and with a lug 6'' connected by a pivot pin 8 with lugs 9 of the casing, the aperture of 65 lug 6'' being elongated to permit of slight play of the valve which is desirable in obtaining a firm seating of the latter on the bottle, as is apparent.

Reference numeral 10 indicates the bottle 70 on the neck 10' of which casing 1 is mounted, the lower end portion of said casing receiving the bottle neck 10' and having screw-threaded engagement therewith, as shown.

Casing 1 can be sealed against removal by 75 unscrupulous persons, in any desired manner. A convenient method however, consists in applying the sealing material, as 11, to the bottle neck and over the lower edge portion of the casing which latter may 80 be cut-out, as at 12, for reception of a portion of the sealing material to obtain a more perfect seal. To close apertures 2 one of which is designed to serve as an outlet port and the other as a vent, closure 3 is 85 screwed downwardly and such movement adjusts device 4 to firmly press and hold valve 6 on the upper edge of the bottle neck 10'.

Having thus described my invention 90 what I claim as new, and desire to secure by Letters Patent of the United States of America, is:—

In combination with a bottle, a casing 95 on the neck of said bottle, said casing having its outer end open and formed in its side wall with a discharge opening, the outer end portion of said casing being screw-threaded, a valve in said casing, a guard in said casing above said valve, said 100

guard consisting of a perforated plate, a closure for the open outer end of said casing, said closure having a screw-threaded flange engaged with the threaded outer end 5 portion of said casing and normally extending over the discharge opening of the latter to close the same, and means within said casing connected to said closure for pre-

venting removal of the latter from the casing, for the purpose specified.

10

Signed at Seattle, Washington, this 7th day of March, 1912.

TOKUTARO NISHIDA.
